(57) **CLAIM**

The ornamental design for a golf shoe outsole, as shown and described.

DESCRIPTION

FIG. 1 is a perspective view of a golf shoe outsole showing our new design;

FIG. 2 is a front view thereof;

FIG. 3 is a rear view thereof;

FIG. 4 is a bottom plan view thereof;

FIG. 5 is a top plan view thereof;

FIG. 6 is a left side elevational view thereof; and,

FIG. 7 is a right side elevational view thereof.

The broken lines showing a shoe upper in FIGS. 1-7 represent the portions of the design that form no part of the claim. The circular shapes shown as broken lines in FIGS. 1 and 4, define the boundaries of the design; with the broken lines themselves and the areas within them, forming no part of the claim.
